UNITED STATES PATENT OFFICE.

ELISHA H. TOBEY, OF DENVER, COLORADO.

RAILROAD-TIE AND RAIL-FASTENING.

SPECIFICATION forming part of Letters Patent No. 249,270, dated November 8, 1881.

Application filed April 6, 1881. (No model.)

To all whom it may concern:

Be it known that I, ELISHA H. TOBEY, a citizen of the United States, residing at Denver, in the county of Arapahoe and State of Colorado, have invented certain new and useful Improvements in Railroad-Ties and Rail-Fastenings; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification, and in which—

15 Figure is a perspective of the rail and tie; Fig. 2, a section through tie and one chair, the other chair being in elevation; Fig. 3, an end elevation of the tie with rail thereon; Fig. 4, a perspective of chair detached from the tie, 20 its parts being separated.

My invention relates to railroad-ties and rail-fastenings; and it consists in the construction and combination of parts hereinafter described, and specifically defined by the claims.

25 In the accompanying drawings, the letter A indicates the channel-iron portion of the tie; B, a wooden cushion set therein, and C the chair which rests upon the wooden cushion and holds the rails D to the ties. A wooden cushion, B, 30 is set in the channel-iron and forms the support for the chair C, which is composed of the two base-plates E E', having the jaws F F'. The base E rests upon the wooden cushion B, base E' upon base E, and the bottom of the 35 rail on base E, while the projecting jaws or

lug F F' fit up underneath the tread and on each side of the web of the rail and on every tie, thereby dispensing with the use of the ordinary fish-plate. The chairs are bolted to the tie by one or more bolts, G, which can be placed either inside or outside of the rails and pass through cushion and channel-iron. The top edges of the channel-iron at the points where the rails bear on the ties is cut away or recessed, as at a, so that the rails may be allowed a slight spring on the wood cushion B without touching the edges of the channel-iron. At the same time, any side thrust or spreading of the track is effectually prevented. The channel-irons can be formed by rolling or bending. The chairs are of cast-iron.

Ties made according to the foregoing description are stronger and more durable than the ties in common use.

Having described my invention, what I claim is—

1. The combination of channel-iron A, wooden cushion B set therein, chair C, and rail D, substantially as set forth.

2. A railroad-tie composed of a channel-iron 60 containing a wooden cushion and provided with recessed edges for the reception of the rails, substantially as set forth.

In testimony whereof I affix my signature in presence of two witnesses.

ELISHA H. TOBEY.
